US00D982549S

(12) **United States Design Patent** (10) **Patent No.:** **US D982,549 S**
Yang (45) **Date of Patent:** **** Apr. 4, 2023**

(54) **HEADPHONE ADAPTER**

(71) Applicant: **SHENZHEN LIANGBAO TECHNOLOGY CO., LTD.**, Shenzhen (CN)

(72) Inventor: **Wukun Yang**, Shenzhen (CN)

(73) Assignee: **SHENZHEN LIANGBAO TECHNOLOGY CO., LTD.**, Shenzhen (CN)

(**) Term: **15 Years**

(21) Appl. No.: **29/777,922**

(22) Filed: **Apr. 9, 2021**

(51) LOC (14) Cl. **14-01**

(52) U.S. Cl.

USPC **D14/205**; D14/217

(58) **Field of Classification Search**

Primary Examiner — Paula Allen Greene

(57) **CLAIM**

The ornamental design for a headphone adapter, as shown and described.

DESCRIPTION

FIG. 1 is a perspective view of a headphone adapter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the headphone adapter that form no part of the claimed design.

1 Claim, 8 Drawing Sheets
